UNITED STATES PATENT OFFICE

JOHN E. KIERNAN, OF BROOKLYN, NEW YORK

DESIGN FOR A MOVING-PICTURE SCREEN

Application filed June 3, 1930. Serial No. 35,890. Term of patent 7 years.

To all whom it may concern:

Be it known that I, JOHN E. KIERNAN, a citizen of the United States, residing at Brooklyn, in the county of Kings and State of New York, have invented a new, original, and ornamental Design for Moving-Picture Screen, of which the following is a specification, reference being had to the accompanying drawing, forming part thereof.

The figure is a front view of a moving picture screen, showing my invention.

I claim:

The ornamental design for a moving picture screen, substantially as shown.

JOHN E. KIERNAN.
